UNITED STATES PATENT OFFICE.

WALTER E. BENNETT, OF BOSTON, MASSACHUSETTS, ASSIGNOR TO THE
MORLEY BUTTON SEWING MACHINE COMPANY, OF SAME PLACE.

LOOP REMOVING AND SPREADING MECHANISM FOR BUTTON-SEWING MACHINES.

SPECIFICATION forming part of Letters Patent No. 399,179, dated March 5, 1889.

Application filed June 14, 1888. Serial No. 277,108. (No model.)

To all whom it may concern:

Be it known that I, WALTER E. BENNETT, a citizen of the United States, residing at Boston, in the county of Suffolk and State of Massachusetts, have invented a new and Improved Loop Removing and Spreading Mechanism for Shank-Button-Sewing Machines; and I do hereby declare the following to be a full, clear, and exact description of the construction and operation of the same, reference being made to the accompanying drawings, forming a part of this specification.

This invention relates to improvements upon the machine for sewing shank-buttons to boots and shoes, (for which Letters Patent were granted to Rosewell Thompson November 30, 1886, No. 353,609,) the stitch formed by said machine at the present time being that for the method of making which Letters Patent were granted to me July 26, 1887, No. 367,334, my object being to remove the secondary loop of thread from the open eye of the needle after it has been drawn up through the fabric, then spread said loop of thread sufficiently wide to pass it over a button-head with the assistance of the take-up and tension mechanisms of the machine, the same being accomplished by the use of a device I term a "loop-taker," having a carrier and other operating mechanisms which regulate and control its position with relation to said needle and loop of thread, all of which will herein be fully explained and described.

In the accompanying drawings, Figure 1 is a left side view of the machine referred to with body shown in section and with the sliding plate, loop-taker carrier, loop-taker, and their operating levers and cams in their proper positions, but with the presser-foot, fabric-feeding, and some of the stitch-forming mechanisms removed, which devices form no part of my present invention. Fig. 2 is an enlarged left side view of the front end of the fabric-supporting table with thread-controller and end of take-up bar in the same. Above the fabric is the front end of the arm of the machine, the needle-bar bearing-support, oscillating needle-bar bearing, needle-bar, sliding plate, loop-taker carrier, loop-taker, and ends of the operating-levers of the latter-named devices, the point of said loop-taker is shown entering the drawn-up loop of thread. Fig. 3 is a front view of the same parts of ma-

chine and devices referred to in above-named figure. Fig. 4 is also an enlarged side view 55 of the thread-controlling device under the fabric, and above the same is the loop-taker carrier, loop-taker, ends of their operating-levers, and lower portion of sliding plate; but with the cover-plate of loop-taker removed 60 from the carrier, so as to clearly show the form and position of the said loop-taker. In this figure the sliding plate, loop-taker carrier, and loop-taker are raised so as to cause the upper surface of the point of the latter to be 65 about the same height as the center of the open eye of the needle, so that when the strain is exerted upon the loop of thread by the take-up and tension devices said loop may be removed from the eye of said needle in consequence 70 of the sloping form and angular position of said loop-taker, the sliding motion of said loop being represented by broken lines in this figure. Fig. 5 is a view of the lower end of the needle and a longitudinal section of 75 the loop-taker through its center and raised to its highest position, as in the preceding figure. This sectional view clearly shows the slot in which the needle enters and the opening for the button-head at the bottom. Fig. 80 6 is a top view of the loop-taker, showing its point entering a loop of thread and the point of the needle in the narrow slot in the loop-taker. Fig. 7 is also an enlarged view of the same devices represented in Fig. 4, but with 85 sliding plate, loop-taker carrier, and loop-taker in a lower position and loop of thread passing down the body of the loop-taker. Fig. 8 is also a representation of said devices, but with the sliding plate, loop-taker carrier, and 90 loop-taker in their lowest position, and with the loop of thread passing under the loop-taker and a button-head. Fig. 9 represents the parts in same position, but with the loop of thread passed under the button-head and 95 drawn snugly around the shank of the button, after which the fabric is moved back by the feeding mechanism, and the loop-taker carrier and loop-taker are raised to about the position shown in Fig. 10, in which position 100 they remain during the formation of the stitch until the secondary loop of thread is drawn up to its highest position by the needle. Then the loop-taker is again lowered, so that the point of the same may enter the loop of 105 thread, as previously shown and described.

Fig. 11 is an enlarged bottom view of the loop-taker carrier and loop-taker. Fig. 12 is an enlarged cross-section of the same on line $x x$, Fig. 10. Fig. 13 is an enlarged cross-section of the loop-taker carrier and its cover-plate on line $x x x x$, Fig. 10.

Similar letters of reference indicate corresponding parts.

A is the body.

10 B is the fabric-supporting table, and C is the arm of the machine.

D is the needle-bar-bearing support.

E is the oscillating needle-bar bearing.

F is the needle-bar.

15 G is the needle-bar carrier.

H is the needle-bar pitman.

I is the needle-bar lever.

J is the take-up bar.

K is the take-up-bar lever.

20 L is the take-up bar and lever-connection.

M is the thread-controller.

N is the thread-controller rod.

O is the thread-roll, and P is the tension mechanism.

25 a is the sliding plate fitted to move upon the front face of the needle-bar-bearing support, and having an extension, a', at its lower end and bent at a right angle, a'', over the lower needle-bar bearing.

30 b is the loop-taker carrier, and is pivoted to the lower side of the angle-plate a''.

b' is the cover-plate of the loop-taker.

c is the loop-taker.

d is the loop-taker carrier-bar.

35 e is the loop-taker carrier-lever.

f is the loop-taker carrier-cam.

g is the sliding-plate lever, and h is the sliding-plate cam.

The practical operation of my improved 40 loop removing and spreading mechanism is as follows: The loop-taker carrier and loop-taker are retained in the position shown in Fig. 10 during the formation of the primary loop of thread and all other parts of the 45 stitch until the needle has drawn the secondary loop of thread up through the fabric and to its highest position above the same, as shown in Fig. 2. Then the carrier and loop-taker are lowered by their operating

50 mechanism to the position shown in this figure, the point of said loop-taker having entered the loop of thread during said lowering movement, as shown in this and Fig. 6. Then said mechanism raises the carrier and loop-taker to the position shown in Figs. 4 and 5, so that the top face of the point of the loop-taker may be at about the center of the open eye of the needle, the narrow slot in the loop-taker making an opening for the point of

55 the needle to enter, as shown in Figs. 5 and 6. While the loop-taker is in this position the take-up and tension mechanisms exert sufficient strain upon the thread to cause said secondary loop to slide out of and away 60 from the open eye of the needle and down the smooth, round, and inclined face of the loop-taker, as shown in Figs. 4 and 7. There

is sufficient space between the loop-taker and its carrier and cover-plate to allow a loop of thread to freely slide in said space; but the 70 loop-taker is retained in its position in said carrier by a portion of the latter and the cover-plate, being curved partially around the back and bottom of said loop-taker, sufficient space being left between said curved portions to allow the free passage of the loop of thread between them while still retaining the loop-taker in its carrier. The curved portion of the carrier and the cover-plate is shown in the enlarged drawings, Figs. 11, 12, 80 and 13. While the loop of thread is thus sliding down the face of the loop-taker, the latter and its carrier are lowered by their operating mechanism, as shown in Fig. 7, until they are in the position shown in Figs. 85 1, 2, 3, 8, and 9, the large opening in the lower end of the loop-taker allowing the same to pass over the button, so that as the strain upon the loop of thread continues to be exerted by the take-up and tension mechanisms said loop may pass under the end of the loop-taker below the horizontal center of the button-head, as shown in Fig. 8, then under the button-head, and be snugly drawn around the shank of the button, as shown in 95 Fig. 9, thus completing the stitch. After the completion of the stitch the carrier and loop-taker are raised to about the position shown in Fig. 10, and the fabric is moved back by the feeding mechanism sufficiently far to 100 sew another button in its proper position upon the same, and after the formation of the primary loop of thread and other parts of the stitch the operations of drawing up the secondary loop of thread, removing it from 105 the open eye of the needle, and spreading and passing it over the button-head are repeated, as above described.

I am aware that prior to my invention various devices have been employed in button-sewing machines to pass a loop of thread over a shank-button head; but 110

I claim as my invention and desire to secure by Letters Patent—

In a shank-button-sewing machine, the 115 combination, with the work-table, open-eyed double-barb needle, stitch-forming tension, and take-up devices and their operating mechanisms, of the loop-taker c and its swinging, rising, and falling carrier b and operating 120 mechanisms, said loop-taker having the point at the top to receive a loop of thread from the eye of the needle, a slot to receive the point of the needle, and an opening at the bottom to receive a button-head and fitted 125 loosely in its carrier, the latter being partially curved around its back and bottom to retain it in its proper working position, and operating substantially as described, for the object set forth.

WALTER E. BENNETT.
